UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR A LATCH-CASE.

SPECIFICATION forming part of Design No. 19,443, dated November 26, 1889.

Application filed October 30, 1889. Serial No. 328,707. Term of patent 7 years.

To all whom it may concern:

Be it known that I, GEORGE S. BARKENTIN, a citizen of the United States, residing at New Britain, in the county of Hartford and State 5 of Connecticut, have invented and produced a new and original Design for a Latch-Case, of which the following is a specification, reference being had to the accompanying drawings, forming part thereof.

10 Figure 1 is a front elevation showing my design. Fig. 2 is a plan view thereof, and Fig. 3 is a sectional view of the upper part of said case on the line $x x$ of Fig. 2.

The leading feature of my design consists 15 in series of raised parallel beads arranged in block-like groups, and in raised rectangular blocks intermediate said groups.

20 A A are the sides of the latch-case, and B the top, the bottom being of the same design as the top. Both of the sides are provided with a vertical bead 3 at each edge and a double bead 4 parallel to the bead 3, but nearest to the edge which forms the face-plate of the case. Between the double bead 4 and 25 the nearest bead 3 there are raised vertical beads in block-like groups 5, and intermediate therewith are plain raised blocks or squares 6. The middle ones of the block-like groups of vertical beads in the top and bottom 30 groups are broken by the screw-holes 7,

around each of which screw-holes is a raised bead 8. The top and bottom edges are of a similar design, having the block-like groups 5 of parallel beads and intermediate rectangular blocks 7. The top and bottom are convex, and are let in between the sides A A, as shown in Fig. 3.

35 What I claim is—

1. The design for a latch-case herein shown and described, the same comprising the sides 40 A A, having vertical beads 3 3 and 4, the said sides, top, and bottom having the block-like groups of parallel raised beads and intermediate rectangular blocks, as set forth.

2. In the design for a latch-case herein 45 shown and described, the side A, having vertical edge beads 3 3 and intermediate double beads 4, the block-like groups 5 of parallel raised beads, and the raised rectangular blocks 6, as set forth.

50 3. In the design for a latch-case herein shown and described, the top and bottom having the block - like groups of parallel raised beads and intermediate rectangular blocks, as set forth.

GEORGE S. BARKENTIN.
